UNITED STATES PATENT OFFICE.

JARED S. LAPHAM, OF NORTHEVILLE, MICHIGAN, ASSIGNOR OF ONE-HALF TO JAMES T. McMAHON, OF TOLEDO, OHIO.

DISHWASHING MACHINE.

Application filed July 31, 1920. Serial No. 400,848.

To all whom it may concern:

Be it known that I, JARED S. LAPHAM, a citizen of the United States, residing at Northville, in the county of Wayne and 5 State of Michigan, have invented certain new and useful Improvements in Dishwashing Machines, of which the following is a specification.

This invention relates to dish-washing 10 machines, and has for its object a number of important improvements which contribute to more efficaciously and expeditiously washing the dishes.

Among these improvements is an improved impeller having its blades twisted 15 to form opposed screw threads to give an endwise as well as upward direction to the spray, which more efficiently cleanses the dishes. The water being thrown alternately 20 endwise in each direction more uniformly and completely covers the entire range of the dishes.

Another feature that I consider of importance is the disposition of the dish racks 25 and the holding means thereon in such a manner that the water is allowed to be thrown between the lower racks without materially impairing its velocity so as to reach dishes in the upper racks properly 30 positioned to thoroughly cleanse and wash them. With this disposition of the dishes provision is also made to allow the dishes to properly drain so that the water that accumulates upon the dishes may be drained 35 off to facilitate the drying of the dishes.

A special arrangement is provided for holding the silverware and like utensils which both exposes these articles to the 40 cleansing effect of the water and at the same time facilitates their drying.

Another improved feature is the use of a screen in connection with the impeller in a position to act as a trap to catch and retain particles in suspension to prevent their being 45 thrown up again by the impeller against the dishes to be washed.

In the drawings,—

Fig. 1 is a perspective of the cabinet, portions being broken away to show the interior 50 construction.

Fig. 2 is a vertical longitudinal section showing some of the dishes in place.

Fig. 3 is a horizontal cross section taken on the line 3—3 of Fig. 2.

Fig. 4 is a view which shows the upper

portion of the cabinet diagrammatically for the purpose of illustrating the throw of the water.

In a prior application #365,760 I have described and claimed some of the features 60 that are contained in the present dish-washing machine, especially the self-drying bearings that are used to support the impeller shaft and the bottom construction of the dish-washing chamber, which serves to return the water at the ends of the impeller. 65 This is described and claimed in this prior application and hence will not be gone into in detail in this case.

Referring to the drawings, *a* indicates the 70 cabinet, which is constructed of sheet metal or other suitable material with angle iron reinforcements *b* at the side corners and at the bottom corners. Rubber-tired wheels *c* are fixed to one end of the cabinet, while 75 rubber-tired castor wheels *d* are provided at the other end of the cabinet. This makes the cabinet portable in the way described in my prior application.

The inferior of the cabinet is divided into 80 an upper and lower chamber by the wall *e* which forms the bottom of the upper chamber which will be called the dish-washing chamber and forms the top of the lower chamber which will be called the motor 85 chamber. It will be noticed that at the left hand side of the cabinet this wall *e* has a sort of center ridge, this ridge running downwardly toward the impeller. The bottom slopes on either side of the ridge toward 90 the end of the impeller *f*. The portion of the wall forming the impeller well has a peculiar form. It rises at the ejecting side of the impeller to form a guard *g* which prevents the returning water from draining 95 back upon the impeller at the ejecting side so as to interfere with the throw of the spray. The water by reason of this guard *g* and the slopes toward the ends is caused to return to the impeller well *h* at the ends. 100

At the bottom of this impeller well is a drain channel *i* which is C shaped in cross section with the opening of the channel facing in a direction counter to the direction of rotation of the impeller. This forms a 105 catch basin or channel to catch the particles in suspension that are thrown out by the impeller. To facilitate the catching of such particles a screen *j* of tubular form is placed in this catch channel, and it will be obvious 110

that when particles of food are thrown against this screen by the centrifugal force afforded by the impeller they will catch on this screen and will be held from again 5 being thrown up by the impeller onto the dishes undergoing cleaning. The bottom of the dish-washing chamber at the opposite side of the impeller does not require a special form of guard and special slopes toward the 10 ends because the water may be returned to the impeller on the non-ejecting side without in any way interfering with the throw of the spray.

The impeller is driven by a motor M 15 located in the motor chamber. This connects with the impeller shaft by a suitable belt *k*. The impeller is of special blade construction and is preferably built of only two blades. These two blades are carried 20 by an impeller shaft and are originally opposite each other on the shaft and lie in the plane of the shaft. The one end of the one blade is then twisted through 90 degrees and the opposite end of the other blade is 25 twisted through 90 degrees. This construction is nicely shown in Fig. 1. This in effect results in a double-threaded screw with oppositely-directed threads of relatively great pitch. Perhaps, it is better described 30 as blades of oppositely-directed spirals. It will be seen, by reference to Fig. 1, that the blades at one end have a spacing of 90 degrees and at the opposite end a spacing of 270 degrees (when considered in the same 35 direction around the shaft). Obviously this produces an unbalanced condition at both ends of the shaft when the impeller is running—a condition that would tend to bend the impeller shaft at the middle and produce undue wear on the bearings at the end. 40 This condition is rectified by the use of suitable counter-weights *l* at opposite sides and ends of the impeller shaft.

Now briefly considered, the advantages 45 of this peculiar type of impeller are that in dipping into the water in the impeller well it does not splash into the water but quietly dips into the water first with the point at one end and then gradually cuts in its full 50 length. This operation of the impeller results in a stream of water that is directed alternately upwardly and toward one end and upwardly and toward the opposite end. This insures the throw of the water through 55 the entire range of the dish-holding racks. Its efficiency is easily determined by the pattern the water throws on the under side of the cover, which shows that the water is thrown on the entire under surface of the 60 cover exposed to the dish-washing chamber and the pattern of the spray shows a uniform throw at all points. Furthermore, with the dishes exposed on the dish racks, as shown in the drawings and which will 65 presently be described, the angular disposi-

tion of the spray toward the ends of the impeller tends to better scour and clean the flat ware while this same angular throw of the spray tends to better clean the hollow ware by setting up vortex whorls in the interior of the cups, glasses, etc. Not only this, but a greater part of the water is thrown to the ends of the impeller by reason of these oppositely-directed spirals of the blades; hence the water returns to the impeller well more quickly and directly. 75

Special attention is drawn to the arrangement of the dish racks, which makes for an even and efficacious distribution of the spray. The flat ware racks are formed by 80 the under supports *m* suitably notched to hold the dishes. A plurality of cross rods *n* located above these cross racks serves to retain the dishes in a near upright position perpendicular with the axis of the impeller shaft and slightly spaced from each other. There are two sets of racks for the flat ware, one on each side of the impeller well, with considerable spacing between these sets of racks. Figs. 2 and 4 show the upper rack, 85 which is a separate stand, provided with legs *o*, connected by reinforcing cross rods *p* and *q*. The stand may be separately lifted out of the dish-washing chamber by the handles *r*. Near the top of the stand is the hollow ware rack itself. This comprises two rows of staggered cross rods *t*, and the end support bars *v*. It is necessary to distinguish between two classes of hollow ware: Shallow hollow ware which approaches flat ware in shape; and deep hollow ware, 90 such as cups, tumblers and bowls. Shallow hollow ware, or even flat ware, may be stacked with great economy of space by placing the first piece in an inclined position in contact with the end support bar *v* as illustrated at the right of Fig. 4 and succeeding pieces in contact with one another. 95 In this arrangement, the narrow passageways left between the pieces lie approximately in the divergent planes of spray projection, which has been found to be necessary for thorough circulation. The same means are employed for the support of deep hollow ware, as shown at the right of Fig. 2 and the left of Fig. 4, in positions which expose the interiors to the direct action of the liquid streams. It will be seen 100 that the same rack may be filled throughout with cups, for example, or if desired with flat ware, and a maximum number of pieces accommodated regardless of their assortment. This is dependent upon the employment of the same dish-holding means in the upper rack for every type of dish. It will be seen 105 from Fig. 2 that the flat ware racks are located above the impeller but are spaced from each other to leave an open space above the impeller to allow the water to be projected directly up into the hollow ware rack. 110

130

However, it is not possible, within the limits of the cabinet of this size, to leave a large enough open space between the two flat ware racks to expose the entire range of the 5 hollow ware rack to the spray from the impeller. Hence the flat ware racks are so arranged as to permit the spray to be thrown between the rims of the plates directly up into the hollow ware rack. This is nicely 10 shown in Fig. 4, where it will be seen that all the hollow ware there shown is exposed to the spray thrown from the impeller either directly through the open space between the racks or else between the rims of the 15 plates. That portion of the spray which impinges upon the concave portion of the plates cleans these plates and is not thereafter called upon for any further cleansing effect whatever. The result of this arrangement 20 of the racks is that, concentrated within in a minimum space, each article to be cleaned has its own fluid stream projected directly against it with unimpaired effectiveness and unpolluted by intermediate contacts, and this is considered essential to 25 successful washing.

At one end of the hollow ware rack is located a wire mesh basket *u* in which the silverware may be stood up on end with the 30 aid of the loop-like rod *v* and the pins *x* secured to the cross bar *y* of the hollow ware stand. It will readily be understood in this position the silverware is much easier to handle, is kept separated, and dries much 35 quicker.

The wooden portions of the racks and stands are all constructed of maple or similar wood, which will not chip, nor is it affected by hot soapy water. The rods are 40 preferably brass rods.

One important feature of my improvement is that the impeller in cooperation with the trough in which it operates will throw a substantially equal amount of spray to 45 each portion of the washing chamber. To accomplish this it is necessary, first, to guard against interference with the outgoing spray by returning liquid; second, to provide means for getting the returning 50 liquid into the path of the impeller blades; and third, to properly direct the throwing of the spray. If the impeller were the full length of the chamber or the liquid containing trough in which it operates, it would be 55 impossible for the liquid to return thereto without greatly interfering with the outgoing spray. By making the impeller

shorter than the width of the chamber and the length of the trough in which it operates and by directing the returning liquid 60 to the ends of this trough, a free return into the path of the impeller blades is provided. If, however, the blades were all parallel to the axis of rotation, the spray thrown out would not exceed the length of the impeller, 65 and consequently, would not reach all portions of the washing chamber. Therefore, I have twisted the blades into opposite spirals, the relative angles being such that the spray from one blade will extend from the wall 70 of the chamber to beyond the center thereof, while the spray from another blade will extend from the opposite wall of the chamber to beyond the center. The combined effect is to cover the entire width of the chamber 75 and to throw this spray uniformly throughout the same. Also, the shield which guards the ascending portion of the impeller blade limits the angle of the spray in the plane of rotation and guards against interference 80 from returning liquid.

What I claim is:

1. In a dish-washing machine, the combination of a cabinet provided with a dish-washing chamber having at its bottom an 85 impeller well which in turn is provided at its bottom with a drainage channel, a tubular screen located in said drainage channel, and an impeller located in said well above said channel. 90

2. A dish-washing machine having in combination a container, means for the support of dishes therein, a trough in the bottom of said container, an impeller rotatable within said trough comprising a pair 95 of blades oppositely inclined to the axis of said impeller and of a length materially less than said trough, and means for directing the drainage from the side toward which said impeller revolves to the ends of the 100 trough outside the impeller.

3. A dish-washing machine having in combination a container, means for the support of dishes therein, a trough in the bottom of said container, a shaft rotatable within 105 said trough, a pair of helicoidal blades of opposite twist and of a length materially less than said trough attached to said shaft, and means for returning the liquid on the discharge side of said trough to the ends 110 thereof and beyond said blades.

In testimony whereof I affix my signature.

JARED S. LAPHAM.
